ABSTRACT

A tube cold rolling mill with rolls the grooves of which are spirally threaded with a variable helix angle and a housing with a drive ensuring its reciprocal-rolling motion relative to the vertical axis so that the angle formed by the housing guides and the axis of rolling corresponds to the helix angle of the roll groove.

TUBE COLD ROLLING MILL

The invention relates to tube cold rolling mills employed in metallurgy.

Commonly known is a tube cold rolling mill comprising a stationary housing for the working stand with rolls, the grooves of which are spirally threaded with a constant helix angle, and a drive with crank mechanism for moving the stand along the housing guides.

The working stand in such rolling mills is displaced at a constant angle relative to the axis of rolling equal to the lead angle of the roll groove, which makes it possible, by increasing the number of turns of the roll groove spiral, to enlarge the deformation zone of the billet and hence to increase the mill rolling rate.

However, the increase of the number of turns of the roll groove leads to increasing the length of rolls and to reducing their rigidity which prevents the quality of product from being improved.

It is an object of this invention to overcome the foregoing difficulty.

The principal object of this invention is to provide a tube cold rolling mill which would improve the quality of product being rolled.

A further object of this invention is to provide shorter and more rigid rolls for the mill.

These objects are attained in a tube cold rolling mill including a working stand with rolls, the grooves of which are spirally threaded, and a drive with crank mechanism for moving the stand along the guides of the housing, wherein, according to the invention, the grooves of the working rolls are spirally threaded with a variable helix angle, while the housing is made so as to allow for a reciprocal-rolling motion relative to the vertical axis and is linked with the stand drive in such a way that the angle formed by the housing guides and the axis of rolling is equal, at each moment of time, to the helix angle of the roll groove spiral, and a crosshead is provided, the housing of which is hinged to connecting rods of the stand drive crank mechanism and has a cavity accommodating a holder, made to turn relative to the vertical axis and hinged to the working stand tie rods and having a hole for passing a billet.

The rolling mill in which the groove of the working rolls is spirally threaded with a variable helix angle, while the housing is made so as to allow for its reciprocal-rolling motion relative to the vertical axis makes it possible to reduce the length of the working rolls, to increase their rigidity, and consequently, to improve the quality of product being rolled.

Preferably the linkage of the stand with the drive can be made as a crank mechanism, the connecting rod of which is hinged to the housing and crank wheel adapted to interact with the gear of the shaft with fitted-on another gear meshing with the stand drive gear.

Such a linkage of the housing with the stand drive ensures reliable and synchronous operation of the drive.

The invention will now be explained in greater detail with reference to an embodiment thereof which is represented in the accompanying drawings, wherein:

FIG. 1 is a plan view with details of the rolling mill, according to the present invention;

FIG. 2 is a view of the working stand with rolls having the threading of groove according to the present invention;

FIG. 3 is a cross-section on the line III—III of FIG. 1.

The rolling mill described in the drawings has a housing 1 (FIG. 1) which is installed so as to ensure its reciprocal-rolling movement relative to the vertical axis 2.

To this aim the housing 1 is hinged to connecting rod 3 links with a crank wheel 4 which is in mesh with gear 5 rigidly fitted on a shaft 6. The other end of the shaft 6 has a gear 7 meshing with a gear 8 of the drive 9. Guides 10 fixed in the housing 1 serve for moving a working stand 11 having working rolls 12 (FIG. 2) with shaped groove 13 which is spirally threaded at a variable helix angle $\alpha_{1,2,3}$ along the groove. The rolls 12 are fitted out with a rack-and-gear drive 14 (FIG. 1).

A crank mechanism 15 is connected to the drive 9 of the stand and the crosshead 18 housing. The latter is, in turn, connected to the working stand 11 with hinged tie rods 17 through a holder 20.

The crosshead 16 (FIG. 3) consists of a split housing 18, the interior of which comprises a holder 20, running in bearings 19, which has a through hole 21 for passing a billet 22. The crosshead 16 is mounted in guides 23 with strips 24 replaced in case of wear.

The rolling mill operates as follows.

The drive 9 reciprocatingly moves the crosshead 16 along guides 23 with the help of the crank mechanism 15. The holder 20 of the crosshead 16 imparts this reciprocating motion to the working stand 11 by means of the tie rods 17. At the same time the motion is transmitted through gear wheels 5, 7 and 8 and shaft 6 to the crank wheel 4 and connecting rod 3 wherefrom it is further relayed to the housing 1 of the working stand 11.

The extreme (dead) positions of the working stand 11 and the crosshead 16 coincide with the extreme (dead) positions of the housing 1, while the laws governing the alteration of the angle of turn of the crank mechanism 15 and the crank wheel 4 with the connecting rod 3 are identical.

We claim:

1. A tube cold rolling mill comprising a stand with rolls having a variable-section groove provided along a spiral line with a variable inclination angle along the groove length; a housing with guides for said stand made so as to ensure its reciprocal-rolling motion relative to the vertical axis; a drive with a crank mechanism for moving the stand along the guides of said housing; a linkage of said housing with the drive of said stand made so that the angle formed by the guides of said housing and the axis of rolling is at each moment of time equal to said variable inclination angle of the roll groove; a crosshead, the housing of which is hinged to a crank mechanism of said stand drive and having a cavity to accommodate a holder; said holder being disposed in said cavity of the housing of said crosshead and able to turn relative to the vertical axis and having a hole for passing a billet and being hinged with tie rods of said stand.

2. A tube cold rolling mill as in claim 1, wherein said linkage of said housing with said stand drive is a crank mechanism comprising a connecting rod connected to said housing, a crank wheel connected to said connecting rod, a shaft having a fixedly mounted first gear linked to said crank wheel, a second gear fixedly mounted on said shaft, and a third gear on said drive of said stand and meshing with said second gear.
